ELECTRICAL WIRING DEVICE

Filed May 12, 1955

2 Sheets-Sheet 2

10 is a second L-shaped metallic member 31 which is formed at its lower end with a rounded portion 32 adapted to conform to the semicylindrical surface of a conductor such as 16 from which the insulation has been stripped. The member 30 is held in position by engagement of its upper bent-over ends with the underside of the cover member 21 as is clearly seen in Figure 5.

Fastened to the member 31 by any suitable means such, for example, as a rivet 33, is a resilient member 34 bearing a contact 35 at its outer end, the contact 35 being preferably of a highly conductive material such as silver. The member 34 is engaged by the cam surface 27 formed on the handle 11 and thus, as the handle is oscillated, the member 34 flexes, causing the outer end thereof including contact 35 to move upwardly and downwardly as seen in Figure 5.

Mounted in slots 36 in the body 10 is an L-shaped member 37 similar to the member 36, this member being formed with a rounded portion 38 which engages another conductor such as the conductor 16a. The member 37 is held in position by the cover member 21 due to the fact that the lower surface of member 21 bears against the upper bent-over horizontal portion of the member 37. Member 37 carries at its upper end a contact 40 which is in vertical alignment with the contact 35 of member 34, this contact 40 being also preferably of silver. Thus when the handle 11 is oscillated to its left hand position as seen in Figures 4 and 5, a circuit is completed from conductor 16 through member 37, contact 40, contact 35 and member 34 to conductor 16a, and when the switch handle is moved to its right hand position member 34 is depressed and the circuit broken at contacts 35 and 40.

A spring member 41 of generally U-shape is positioned in the slots 42 in the body portion 12 which slots extend forwardly from the rear portion 43 of the housing 10. The member 41 has the base portion thereof lying against the rear portion 43 of the housing and has the terminal portion 44 extending across the aperture 45 in the rear of housing 10 through which aperture the conductor 16 passes. The terminal 44 of member 41 has a sharp edge which, when a wire such as 16 is inserted through the aperture 45 (as shown in Figure 5), bears against that wire and prevents removal thereof. It will be noted that the member 41 has a bend 46 therein adjacent the opposite end which causes the member to exert a considerable resilient force against a conductor such as 16 when positioned as described.

The member 41, which has thus far been described, is in the left hand portion of the housing as seen in Figure 5 and cooperates with the conductor 16. An exactly similar member 41 is positioned in the right hand portion of the housing and cooperates with a conductor such as 16a. Moreover, the two members 41, which have been described above, cooperate with the terminal members 31 and 37. Similar members 41 are positioned in the forward portion of the housing as seen in Figure 8, these members cooperating with conductors in the same manner as do the first described members 41. However, in the particular embodiment shown, a means is provided for making a connection through the housing body 10 so that the other side of the circuit which has no switch therein can be more readily wired since no splice is necessary but instead the connection may be made by simply inserting the two wire ends in apertures 45 in the housing. This is accomplished by means of a cross-over member 47 which is of U-shaped form as seen particularly in Figure 10, the ends of the arms of the U being rounded as indicated at 48 to cooperate with the conductors and there being extensions 50 on each end of the member 47 which extensions are bent over so that the cover member 21 holds the member 47 in place in the slots 51.

Referring now to Figures 2 and 3, it will be seen that

the body member 10 is provided with slots 52 adjacent the apertures 45 and further that the slots 52 are in alignment with the terminal ends 44 of the members 41. Additionally, the slots 52 extend from approximately the center line of aperture 45 to the edge of the housing and thence forwardly in the side wall of the housing. Slots 52 are wide enough so that the blade of the usual screwdriver customarily carried by electrical installers may be inserted therein. Thus, as is seen in Figure 1, a screwdriver such as 17 may be inserted in one of the slots 52 and when pressed forwardly will press the terminal end 44 of the corresponding member 41 forwardly moving the edge thereof forwardly and out of engagement with the corresponding conductor such as 16, thus freeing the conductor for removal from the corresponding terminal 31 and permitting it to be removed through the aperture 45.

Since wiring devices such as switches and plug receptacles are fastened in position by means of screws 20 which extend through the mounting plate 12 and are threaded into gears on the outlet box, it is necessary that the installer carry a screwdriver at all times, but this screwdriver is relatively large and cannot be utilized when the slots 52 extend only from adjacent the center 25 of the apertures 45 to a point near the side wall of the housing body 10. Moreover, when the slots 52 are formed in the rear wall only it is necessary to insert the screwdriver blade from the rear and frequently the wiring device cannot be removed sufficiently far from the wall to permit the insertion of a screwdriver having a normal length blade and handle. Consequently, the 30 installer is compelled to carry a special tool or at best a short, narrow bladed screwdriver which can be utilized for releasing wires from the terminal members of the 35 wiring device.

As will be seen, by extending the slots 52 to the side wall and forwardly, no special tool is necessary to release the circuit conductors from the switch terminals and therefore the wiring device of this invention is of 40 great practical advantage.

While I have described a preferred embodiment of the invention, it will be understood that I wish to be limited not by the foregoing description, but solely by the claims granted to me.

45. What is claimed is:

1. An electrical wiring device comprising, in combination, a hollow body of electrically insulating material forming a housing, said housing having at least rear, end and side wall portions, a wire engaging member extending forwardly from said rear wall, an aperture in said rear wall adjacent said wire engaging member, a wire gripping member extending across at least a portion of said aperture, said gripping member being resilient and inclining from the rear toward the front whereby said member serves to press a wire extending through said aperture against said engaging member, and a slot extending from a point adjacent the center line of said aperture on the side opposite said wire engaging member to the adjacent side wall and forwardly in said side wall, said slot providing ingress for a tool through said side and rear walls for pressing said gripping member forwardly to thereby release a wire held between said engaging and gripping members.

2. An electrical wiring device comprising, in combination, a hollow body of electrically insulating material forming a housing, said housing having at least rear, end and side wall portions, an aperture in said rear wall, a wire gripping member with an edge extending across at least a portion of said aperture, said edge being resiliently supported with respect to said housing, for gripping a wire extending through said aperture, a slot in said rear wall, the forward projection of which intercepts a portion of said gripping member, said slot extending to the edge of the rear wall and forward in the side wall to a point forward of the gripping member, whereby ingress is pro-

vided for a tool through said side and rear walls for pressing said gripping member forward to release a wire retained by the device.

3. An electrical wiring device, comprising in combination, a hollow body of electrically insulating material forming a housing, said housing having at least rear, end and side wall portions, a wire engaging member within said housing, an aperture in said rear wall adjacent said wire engaging member, a wire gripping member with an edge extending across at least a portion of said aperture, said edge being resiliently supported with respect to said housing whereby said member serves to press a wire extending through said aperture against said engaging member, a slot in said rear wall, the forward projection of which intercepts a portion of said gripping member, said

slot extending to the end of the rear wall and forward in the side wall to a point forward of the gripping member whereby ingress is provided for a tool through said side and rear walls for pressing said gripping member forward to release a wire retained by the device.
